US0D1038092S

(12) **United States Design Patent** (10) Patent No.: **US D1,038,092 S**
(45) Date of Patent: ** Aug. 6, 2024

(54) **REMOTE CONTROLLER**

(71) Applicant: **YAMAHA CORPORATION**,
Hamamatsu (JP)

(72) Inventor: **Ryo Suzuki**, Hamamatsu (JP)

(73) Assignee: **YAMAHA CORPORATION**,
Hamamatsu (JP)

(**) Term: **15 Years**

(21) Appl. No.: **29/884,272**

(22) Filed: **Feb. 9, 2023**

(51) LOC (14) Cl. 14-03

(52) U.S. Cl. ..... USPC **D14/218**

(58) **Field of Classification Search**

(57) **CLAIM**

The ornamental design for a remote controller, as shown and described.

DESCRIPTION

FIG. 1 is a top perspective view of a remote controller showing my new design;

FIG. 2 is a bottom perspective view thereof;

FIG. 3 is a front view thereof, the rear view being a mirror image thereof;

FIG. 4 is a top view thereof;

FIG. 5 is a bottom view thereof; and,

FIG. 6 is a left side view thereof, the right side view being a mirror image thereof.

The broken lines shown represent portions of the remote controller and form no part of the claimed design.

1 Claim, 6 Drawing Sheets
